CARBURETOR

Henry Hueber, Buffalo, and Erwin C. Horton,
Hamburg, N. Y., assignors to Trico Products
Corporation, Buffalo, N. Y.

Application January 20, 1930, Serial No. 422,893

11 Claims. (Cl. 261—34)

This invention relates to a fuel carbureting device for internal combustion engines and is primarily adapted for the motor vehicle engine of this type.

5 In the normal operation of the motor vehicle the driver will depress his accelerator pedal to increase the speed of the engine, and when the accelerator is quickly depressed there is a brief interval of time before the engine responds to 10 the sudden acceleration demand. At times the demand is not satisfied, and the engine does not pick up with sufficient rapidity, to such an extent that the action of the engine might appear sluggish and retarded. Such slowness in response is due largely, if not altogether, to the fact that 15 the combustible mixture is for the moment rendered too lean by the sudden gust of air which rushes in upon the opening of the throttle without a corresponding increase in the feed of gasoline. The liquid feed does not respond readily by 20 reason of the column of liquid which must be moved by the induced action of the inrushing air.

The present invention aims to provide a carburetor which will maintain the proper proportion 25 of air and gas entering into the combustible mixture both during the normal running of the engine as well as during an acceleration thereof; to provide the fuel passage, adjacent the fuel nozzle of the carburetor, with a device which will render the liquid fuel column more sensitive and 30 responsive to variations in the air currents enveloping the fuel nozzle whereby the induced lifting action on the column of liquid for the moment of sudden acceleration is hastened; and to 35 provide a controlled air inlet for the carburetor working in conjunction with the liquid control device whereby a combustible mixture of a uniform grade will be delivered by the carburetor to the engine during all periods of operation.

40 The invention also has for its object to provide a carburetor which will enable a more rapid pick-up or "get-a-way" and which will avoid the sluggish operation of the motor vehicle engine due to an over lean combustible mixture during 45 the initial period of an acceleration demand.

The invention also has for its object to provide a simplified carburetor construction lacking the well known float chamber, and further, to provide a carburetor with improved means for enriching the combustible mixture for priming purposes.

Further the invention resides in the arrangements and combinations of the gas and liquid controls and the associated parts, all as is more 55 fully set forth in the following description and

claims, reference being had to the accompanying drawing in which the view is a vertical section, with parts in elevation, through a carbureting apparatus embodying the present invention.

Referring more in detail to the accompanying drawing, the numeral 1 designates the fuel line and 2 the air chamber, the former having a fuel nozzle 3 controlled by the valve 4 and discharging within the atomizing chamber 5 at a point beneath the throttle valve 6. The usual idling jet 7 may be provided when desired.

The fuel line 1 is provided with a chamber 8 preferably enlarged and communicating through one or more orifices 9 with an underlying sediment trap 10 into which the supply pipe 11 delivers the gasoline from the supply tank 12. A screen or other filter 13 may be provided in the upper portion of the sediment trap 10 to purify the liquid. The fuel is, therefore, lifted direct from the supply tank rather than through the 75 vacuum tank and float chamber of the carburetor.

Within the fuel line is provided means for momentarily displacing a portion of the liquid therein during the initial period of acceleration whereby it will become unnecessary to move immediately the entire column of liquid between the nozzle and the tank. This means in the preferred embodiment comprises a yieldable or flexible wall 80 for responding to fluid pressure conditions in said line and adapted for being readily displaced 85 thereby. To gain greater sensitiveness and responsiveness to the pressure conditions we have inserted this flexible wall in the enlarged chamber 8 whereby a larger wall surface is obtained for the fluid pressure to act upon. This flexible wall 90 is herein depicted as being in the form of a diaphragm 14, and when the butterfly or throttle valve 6 is opened to accelerate the engine speed the sudden increase in the volume of air passing over and about the nozzle 3 will produce a greater 95 eductive force and cause an increased discharge of the fuel from the nozzle 3. This demand for an increased supply of fuel has in the past been difficult to meet by reason of the column of liquid which was required to be acted upon and therefore resulted in a leaner mixture for the initial 100 period of acceleration and a consequent lagging in engine response.

With the improved construction, the increased suction about the nozzle 3, which is produced upon opening the throttle, will cause the fuel in the feed line to move more rapidly at the outstart because in lieu of moving the entire column of liquid from the supply tank 12, the flexible wall 14 will displace a portion of the liquid by moving or 110

yielding inwardly to accommodate the increased demand, and after the fuel feed has resumed its new normal or operating flow the flexible wall will return outwardly to its normal. Because of the 5 displacing action of the wall 14 the liquid will well up in the nozzle and pass with increased flow into the augmented air stream toward the maintenance of a uniform mixture.

The air chamber 2 is provided with an inlet 10 opening or port 15 having a valve or closure plate 16 pivoted at 17 for movement toward and from its seat. The valve 16 is yieldably held closed by a spring 18 which is compressed between the valve and a collar 19 in turn adjustably supported by 15 the screw 20 so as to vary the spring tension or pressure exerted by the spring on the valve. The collar 19 in its practical embodiment may be carried by a stem 21 slidably mounted within the screw 20, threaded through a wall of the air chamber, and is adapted to be temporarily depressed by a priming control 22, whereby an increase in the spring pressure may be temporarily provided to restrict or retard the opening of the valve 16 and the admission of air to the carburetor 20 thereby insuring a richer mixture for starting the engine. The port 15 is preferably disposed in opposition to the diaphragm 14 so as to 25 simplify the connection between the valve and said diaphragm. This connection may consist 30 simply of a single link or rod 23 which will transmit the movement of the diaphragm to the air valve, and vice versa, whereby the uniformity of the combustible mixture is maintained not only throughout the normal operation of the vehicle 35 but also during sudden accelerations thereof.

Furthermore, any priming pressure on the 40 spring 18 will be more or less transmitted to the diaphragm with a resultant displacement of the fuel in the fuel line and a rise of the liquid in the nozzle.

The operation of the improved carburetor is 45 briefly described as follows:—In starting the engine by means of a priming operation, the lever 22 is actuated to urge the air valve 16 closer to its seat, and any movement of the valve 16 will be 50 transmitted through the connecting link 23 to the diaphragm 14 which, when pressed inwardly, will cause the gasoline to well up into the nozzle 3 so as to be more readily enriched and be acted upon 55 by the nozzle-enveloping air currents.

With the priming lever 22 released, the air valve 60 16 will open to its normal position substantially as indicated in the drawing, or to such extent as to supply the requisite volume of air for the effective carburetion of the liquid fuel. When an accelerated action is desired, by a further opening 65 of the throttle 6, an increased air supply will result, and during the operation of the ordinary carburetor this volume of air is momentarily increased more rapidly than the liquid fuel can be supplied thereto, resulting in a leaner combustible mixture insufficient to maintain the engine active up to its normal efficiency.

However, in the improved carburetor the opening 70 of the air valve is resisted or opposed by the fuel displacing device 14 which in turn is acted upon by the pressure variation in the liquid fuel line. The sudden increase in the volume of air passing the fuel nozzle 3 is thus enriched by a more or less corresponding increase in the fuel 75 therefrom, and with the sudden flow or spurt of the liquid fuel in the fuel line the diaphragm 14 will yield inwardly and urge the valve 16 toward its seat for the moment of acceleration, or until 80 the fuel flow through the feed line accommodates

itself to the accelerated conditions whereupon the diaphragm 14 will return to its new normal as defined by the volume of air passing through the port 15. In other words, the tendency for the valve 16 to open and remain open and admit the 85 increase in the air volume called for by the opening of the throttle has a counter-force in the diaphragm 14 responding to the sudden and momentary pressure reduction in the feed line, the counter-acting effect resulting in a controlled or measured inflow of air sufficient to carburet the increased fuel feed whereby the elements entering into the combustible mixture substantially maintain their proper proportions to render the combustible mixture substantially uniform throughout the accelerating period. The air valve thus aids in returning the displacing member 14 to a non-displacing or inoperative position. As soon as the entire fuel column between the supply tank and the nozzle catches up and accords with its new flow, required by the accelerating action of the engine, the diaphragm 90 14 will gradually respond to the urge or pull exerted by the valve 16 so that the volume of air admitted to the carburetor will be gradually increased in substantial proportion to the increased supply of fuel to the nozzle 3. As the pressure maintaining in the passage 5, adjacent the mouth of nozzle 3, will be sufficient to prevent retrograde movement of fuel in the passages 95 1 and 3, full opening movement of the valve 16, following the initial accelerating action, will cause the diaphragm 14 to raise, lifting fuel from the tank 12 through the line 11 into the chamber 8. This lifting action will accelerate the flow of 100 fuel through the fuel line 11, enabling it to catch up with the accelerated flow of fuel through the passage 1 and nozzle 3. This action is of particular importance where the fuel line 11, which may extend to a supply tank, vacuum tank, or 105 fuel pump, is of comparatively great length and consequently contains a large volume of fuel having correspondingly large inertia.

Thus the action of the carburetor expeditiously 110 provides an increased volume of uniform combustible mixture when suddenly called upon therefor, and maintains the gas uniform throughout the acceleration of the engine.

What is claimed is:

1. A carburetor comprising an atomizing chamber, a co-operating fuel nozzle associated therewith, a fuel passage leading to the nozzle and having a flexible wall displaced by and in response to pressure variations in the passage, 115 an air chamber communicating with the atomizing chamber and having a port opening to the atmosphere in opposition to the flexible wall of the fuel chamber, a valve controlling the air flow through said air port, and motion transmitting means connecting the air valve to the flexible wall whereby the opening movement of the valve is resisted and controlled by an outward flexing of the wall.

2. A carburetor comprising an atomizing chamber, a fuel nozzle associated therewith, a fuel passage leading to the nozzle and having an enlarged chamber formed with a diaphragm, an air chamber communicating with the atomizing chamber and having a port opening to the atmosphere, a valve controlling the air flow through said air port and opening in a direction away from the diaphragm, a link connecting the air valve to the diaphragm whereby the opening movement of the valve is resisted by an outward 140 flexing of the diaphragm.

- flexing of the diaphragm, and means for exerting a counter-acting pressure on the valve-diaphragm unit for resisting and controlling opening movement of the valve.
3. A carburetor comprising an atomizing chamber, a fuel nozzle discharging therein, a fuel passage leading to the nozzle and having a flexible wall, an air chamber communicating with the atomizing chamber, a valve controlling the air flow through said air chamber, a link connecting the air valve to the flexible wall whereby the opening movement of the valve is resisted by an outward flexing of the wall, and a spring for urging the valve to a closed position.
- 10 4. A carburetor comprising an atomizing chamber, a cooperating fuel nozzle, a fuel passage leading to the nozzle and having an enlarged chamber formed with a flexible wall, an air chamber communicating with the atomizing chamber and having a port opening to the atmosphere, a valve controlling the air flow through said air port and opening in a direction away from the flexible wall, a link connecting the air valve to the flexible wall whereby the opening movement of the valve is resisted and controlled by an outward flexing of the wall, a tubular member adjustably disposed in opposition to the valve, a stem slideable in the tubular member and carrying a collar in opposition to the air valve, a spring compressed between the collar and the air valve for urging the latter to its seat, and means for shifting the stem to resiliently urge the air valve toward its seat for priming purposes.
- 15 5. A carburetor comprising an atomizing chamber, a fuel nozzle discharging therein, a fuel passage leading to the nozzle, a flexible wall in said passage, an air chamber communicating with the atomizing chamber and having a port, a valve controlling the air flow through said air port, means connecting the air valve to the flexible wall whereby the opening movement of the valve will be resisted by an outward flexing of the wall, and means for moving the air valve toward its seat and through said connecting means flex the wall inwardly thereby to exert an increased pressure on the fuel line for priming purposes.
- 20 6. A fuel feed system comprising a supply tank, a carburetor having an atomizing chamber and a cooperating fuel nozzle, said body having an air port, a valve for controlling the passage of air through the port, a fuel line connecting the tank to the carburetor, a member responsive to pressure variations in the fuel line, and means connecting said member to the air valve whereby responsive action of said member will correspond to the movement of the valve toward and from its seat to effect a substantially uniform proportionment of the carbureting air to the supplied fuel whereby a uniform combustible mixture results.
- 25 7. In a fuel feeding system, the combination with a supply tank, a carburetor having an atomizing chamber and a nozzle discharging therein, and a fuel line connecting the nozzle to the supply tank, of means for exerting a displacing pressure upon the fuel in the said fuel line at a point adjacent the nozzle, and an air valve for admitting air to the carburetor and connected to said displacing means to act by and during opening movement of the valve for urging the displacing means to its inoperative position.
- 30 8. In combination with a source of fuel supply, a carburetor and a fuel supply line connecting said source and said carburetor, the latter having an air valve, a fuel discharge nozzle, a fuel passage connecting said supply line and said nozzle, and a flexible portion in a wall of said fuel supply line operably associated with said air valve and said fuel passage to increase the volume of said fuel passage upon opening movement of said air valve, whereby opening movement of said valve will effect an acceleration of fuel in said passage and supply line between said source and said means.
- 35 9. A carburetor comprising an atomizing chamber, a fuel nozzle associated therewith, a fuel passage leading to the nozzle and having a chamber, a member movable into the passage chamber for displacing fuel therein, an air inlet passage into the atomizing chamber, a valve controlling the air flow through said air inlet passage, and means connecting the displacing member to the air valve for transmitting movement therebetween to effect displacing action of said member when said valve closes, the fuel passage in the carburetor being constantly open to fuel flow into said atomizing chamber whereby fuel may flow into the atomizing chamber regardless of the positions of said air valve and said movable member.
- 40 10. In a carburetor, an atomizing chamber, a fuel nozzle associated therewith, a fuel passage for normally conducting fuel to said nozzle, a closed chamber in the fuel passage adjacent the nozzle, a throttle valve, a fluid responsive member movable in accordance with the position of the throttle valve by fluid passing thereby, and means operable by said fluid responsive member for enlarging and contracting said chamber as the flow of fluid past said throttle valve respectively increases and decreases.
- 45 11. A carburetor comprising a body having an atomizing chamber and a cooperating fuel nozzle, a fuel passage for conducting fuel to said nozzle, said body having an air port, a valve for controlling the passage of air through the port, and means for automatically increasing the supply of fuel passing through the fuel passage to the nozzle when the air valve is closing, said passage between the means and nozzle being open for fuel passage irrespective of the position of said valve.
